UNITED STATES PATENT OFFICE.

PAUL L. L. YORGENSEN, OF HARTFORD, CONNECTICUT.

WRENCH-HOLDER.

1,172,656.

Specification of Letters Patent.

Patented Feb. 22, 1916.

Application filed September 28, 1915. Serial No. 52,982.

To all whom it may concern:

Be it known that I, PAUL L. L. YORGENSEN, a citizen of the United States, residing at Hartford, in the county of Hartford and State of Connecticut, have invented certain new and useful Improvements in Wrench-Holders, of which the following is a specification.

This invention relates to a wrench holder. 10 While the device is probably susceptible of general use it was primarily designed and is especially intended for use in conjunction with those wrenches which are used for applying or removing hollow screws. 15 A wrench of this character has a shank or body and a head at an angle to the body or shank, the operative portion of the head being of a shape to correspond with the socket of the hollow screw in connection with 20 which said wrench is to be used. These heads vary in shape, as will be obvious. These wrenches are light and being subjected to strains and stresses not only bend but break down. I provide a holder for 25 this type of wrench which materially reinforces the latter, strengthening it in fact to such an extent that the life thereof is materially prolonged.

In the drawings accompanying and forming part of the present specification I have shown in detail one convenient form of embodiment of the invention which to enable those skilled in the art to practise the same will be set forth fully in the following description. I do not restrict myself to this particular disclosure; I may depart therefrom in several respects within the scope of the invention defined by the claims following said description.

40 Referring to said drawings: Figure 1 is a top plan view. Fig. 2 a bottom plan view, and Fig. 3 a longitudinal section of a holder involving the invention. Fig. 4 is a side elevation of said holder showing a wrench carried thereby. Fig. 5 is a detail view of the wrench.

Like characters refer to like parts throughout the several views.

In Fig. 5 I have shown a socket or hollow 50 screw wrench. This wrench has an elongated shank or body 3 and a head 4. The head 4 is at an angle to the shank or body 3. This angle may vary. As illustrated the head is united with the shank upon a curve. 55 The cross sectional form of the wrench may vary. That shown is hexagonal.

The holder is denoted in a general way by 5 and its longitudinal shape approximately corresponds to that of the wrench. The body 6, however, of the holder is longer 60 than the body of the wrench, while the head 7 of the holder is shorter than the head of the wrench.

The holder 5 is provided with a seat for 65 the wrench. This seat may be of any suitable character which will properly receive the wrench. As shown the seat is formed partly in the body 6 and the remainder in the head 7, the seat following practically the form of the head and body. The handle 6 70 as shown has a longitudinally extending groove or channel 8 therein, while the head 7 has a hole 9, the hole or opening being inclosed and the channel or groove 8 leading into or communicating with the hole 9, the 75 channel 8 near its forward end being bent to conform to the curvature of the bend at the head 7 and shank 6. This hole 9 is inclosed.

To use the wrench in connection with the holder 5, the head 4 of the wrench will be 80 passed through the hole 9 and the shank 3 then dropped into the channel 8, the channel being of such a shape as to comparatively closely or snugly receive the shank of the wrench. The head 4 of the wrench also 85 comparatively closely fits the hole 9, so that when the wrench and the holder are in operative relation, there will be no lost motion between the two. When, therefore, the holder is connected with the wrench and 90 when the wrench is used, it is so strengthened as to virtually prevent, certainly under ordinary conditions, the bending of the wrench and the breaking down of the head. The channel or groove 8 is slightly longer 95 than the shank of the wrench 3. This, however, is a detail.

What I claim is:

1. A holder for wrenches of the class described, comprising a body provided with a 100 head at an angle thereto, the body and the head having jointly a wrench seat and that part of the seat which is in the body being in the form of a longitudinally extending groove.

2. A holder comprising a body provided with a head at an angle thereto, the body having a longitudinally extending groove and the head an inclosed hole into which the groove leads.

3. A holder comprising a body having a head at an angle thereto, the body being

5 united with the head upon a curve and having a longitudinally extending groove, the head having an inclosed hole and the groove and hole being connected with each other upon a curve conforming practically to that between the head and the body.

In testimony whereof I affix my signature in presence of two witnesses.

PAUL L. L. YORGENSEN.

Witnesses:

L. L. MARKEL,
HEATH SUTHERLAND.
